UNITED STATES PATENT OFFICE.

CHARLES T. WAGNER, OF COLLEGE POINT, NEW YORK.

DESIGN FOR QUILTING.

SPECIFICATION forming part of Design No. 18,404, dated June 19, 1888.

Application filed February 16, 1888. Serial No. 264,273. Term of patent 7 years.

To all whom it may concern:

Be it known that I, CHARLES T. WAGNER, of College Point, Queens county, and State of New York, have originated and produced a new Design for Quilting, of which the following is a specification.

My design relates to quiltings which are manufactured for linings for skirts, for garments, and for bed-coverings.

The design comprises, in combination, a number of rows or pairs of intersecting circles. The pairs of intersecting circles in alternate rows are arranged in line, but the pairs of intersecting circles of intermediate rows are arranged opposite the spaces between the pairs of intersecting circles in the rows first mentioned. Between each pair of circles and the next adjacent pair of circles in the same row two pairs of reversed oblique lines extend, and between these pairs of oblique lines are semicircles. The semicircles connecting certain of said oblique lines intersect the pairs of intersected circles of the next adjacent rows.

In the accompanying drawing I have represented a piece of quilting ornamented with my design.

$a' a^2$ are pairs of intersected circles arranged in a row. $a^3 a^4$ designate other pairs of intersected circles, of which there will also be rows corresponding to the rows of circles $a' a^2$. The various pairs of intersected circles are there-

fore staggered. The pairs of circles $a^3 a^4$ are arranged opposite the spaces between the pairs of circles $a' a^2$. Between the circles $a' a^2$ two pairs of reversed oblique lines or ogee curves $b' b^2$ extend. Between the ends of the oblique lines or ogee curves b' semicircles b^3 are arranged, and between the ends of the oblique lines or ogee curves b^2 semicircles b^4 are arranged. Certain of the oblique lines or ogee curves $b' b^2$ cross each other and certain of the semicircles which I have mentioned intersect the intersected pairs of circles. This combination of lines forms a great variety of figures, according as different pairs of such lines may be viewed, the central figure being outlined by the lines $b' b^2$ and semicircles $b^3 b^4$.

What I claim as new, and desire to secure by Letters Patent, is—

The design for quilting, consisting of staggered rows of pairs of intersected circles, pairs of reversed oblique lines extending from adjacent pairs of circles, and semicircles arranged between the said oblique lines, the various lines being so disposed that certain of the oblique lines will cross and certain of the semicircles will intersect the pairs of circles, substantially as shown and described.

CHAS. T. WAGNER.
